UNITED STATES PATENT OFFICE.

ALBERT G. SCHERER, OF CHICAGO, ILLINOIS, ASSIGNOR TO THE EXCELSIOR STEEL FURNACE COMPANY, OF CHICAGO, ILLINOIS, A CORPORATION OF ILLINOIS.

BOOT FOR HOT-AIR STACKS.

Application filed January 7, 1926. Serial No. 79,746.

My present invention relates to improvements in boots for hot air stacks, and has special reference to the provision of means for drawing such boots with such degree of force as may be necessary into the desired relation with the hot air stack and the joists and studding of buildings with which they are designed to be assembled, and after they are so drawn into position to securely and dependably anchor or secure them in place.

Hot air stacks consist of sheet metal conduits of rectangular cross-section installed between the studding of buildings for the purpose of conveying hot air from the furnace to the portions of the building which it is desired to heat. The hot air is uniformly conveyed from the furnace to the bottom of the stacks in or by means of a round pipe, and the fitting by means of which assembly is made between the round pipe from the furnace and the rectangular stack between the studding is called a boot. There is little room behind the boot or between the sides of the boot and the joists for manipulation. The present practice is to rivet straps of tin to the top of the boot and insert it between the joists and press it up by hand as carefully as may be until it is believed that satisfactory assembly has been secured between the boot and the stack, and then the straps are nailed to the joists to secure or anchor the boot in position. Because of lack of room between the sides of the boot and the joists it is difficult to properly nail the holding straps in position and it is difficult to press the boot up into proper assembly with the stack with only the force of the hands and arms operating against the bottom of the boot, and the boot does not always stay in position while the straps are being nailed to the joists. Means are usually provided upon the stack and boot for securing an interlocking assembly between them and in order to cause this means to function sufficient, controlled, uniform pressure must be applied to the boot. It has therefore been my object to provide simple means in connection with boots for hot air stacks by means of which they may be drawn with any degree of force which is necessary into position between the joists and into assembly

with the hot air stacks and which will secure them dependably and permanently in their proper position.

I prefer to secure the foregoing object by means of the structure illustrated in the accompanying drawing, in which—

Fig. 1 is a vertical side elevation, partially in section, showing the relation of stack, floor, joist, and boot about to be assembled with my assembling and securing means applied thereto;

Fig. 2 is a front elevation of the structure shown in Fig. 1, the joists, floor and studs being shown in section, and an elbow in the round pipe from the furnace being shown in assembly with the boot;

Fig. 3 is a similar view to that shown in Fig. 2, except that the parts are in completely assembled position.

Similar reference characters refer to similar parts throughout the several views.

I have illustrated a typical boot construction. In Figs. 1, 2, 3 the assembly with the round pipe from the furnace is made from the bottom of the boot and the boot consists of rectangularly arranged rear and side walls 6 and 7. The front edge of the side walls extends rearwardly from the lower front corner to a sufficient distance in front of the top rear corner to arrange for assembly with the hot air stack. The front wall 8 joins with the slanting portion of the side wall 7 and the lower edges of the front, rear and side walls are connected by a bottom plate provided with a circular aperture to which is secured a collar 9 for receiving elbow 10 of the cylindrical pipe running from the furnace. The upper edges of the rear, front and side walls are bent to provide shoulders, as at 11, and then extend upwardly, as at 12, to telescope or slip within the walls of the rectangular stack 13. The upward extensions 12 are preferably provided with an outwardly extending angular bead 14 adapted to be forced within a restriction 15 in the stack so as to lock the stack and boot together. The forcing of these parts together requires the firm and regulated application of the parts one to the other.

I provide on the sides of the collar 9 at diametrically opposite locations two parallel slots 16 and force the metal from between

the slots out as at 17 so as to permit of the introduction of a wire 18 therethrough. For the utilizing of these wires all that it is necessary to do is to nail suitable nails 19 in an upwardly inclined direction through the joists 20 above the places of attachment to the boot of the wire and to loop the wires over said nails 19 when, by pulling downwardly upon the wire, in which position a great deal of force can be easily applied, it will cause the boot to be surely and snugly drawn into the desired position. It will also be seen that the wire after being employed for drawing the boot into position, can then be twisted upon itself as at 21 to hold many times greater force than the normal use of the structures will ever

throw upon it. In the drawing I have illustrated the relation of the joists 20 with the floor 22 and studding 23.

20

Having described my invention what I claim as new and desire to secure by Letters Patent is:

1. In combination with hot air boots lengths of wire secured to and extending from diametrically opposite points adjacent the bottoms of said boots.

2. In hot air boots having a pair of parallel slots located on their sides adjacent their lower edges, a separate length of wire extended through and from each of said slots.

ALBERT G. SCHERER.
